United States Patent Office

Des. 182,370
Patented Mar. 25, 1958

182,370

BUILDING

Walter P. Margulies, Scarsdale, N. Y., assignor to United Merchants and Manufacturers, Inc., New York, N. Y., a corporation of Delaware

Application January 16, 1957, Serial No. 44,511

Term of patent 14 years

(Cl. D13—1)

Fig. 1 is a perspective view of a building, showing the front and one side of my new design;

Fig. 2 is another perspective view, of the same building, showing the rear and other side; and

Fig. 3 is a plan view of the building.

I claim:

The ornamental design for a building, as shown.
